(57) **CLAIM**

The ornamental design for a personal mobility device, as shown and described.

DESCRIPTION

FIG. 1 is a front view of a personal mobility device according to the novel design in an open/unfolded configuration.

FIG. 2 is a back view of a personal mobility device according to the novel design in an open/unfolded configuration. FIG. 3 is a left side view of a personal mobility device according to the novel design in an open/unfolded configuration; the right side view is a mirror image of the left side view.

FIG. 4 is a top view of a personal mobility device according to the novel design in an open/unfolded configuration.

FIG. 5 is a bottom view of a personal mobility device according to the novel design in an open/unfolded configuration.

FIG. 6 is a perspective view of a personal mobility device according to the novel design in an open/unfolded configuration.

FIG. 7 is a front view of a personal mobility device according to the novel design in a closed/collapsed configuration.

FIG. 8 is a back view of a personal mobility device according to the novel design in a closed/collapsed configuration. FIG. 9 is a left side view of a personal mobility device according to the novel design in a closed/collapsed configuration; the right side view is a mirror image of the left side view.

FIG. 10 is a top view of a personal mobility device according to the novel design in a closed/collapsed configuration.

FIG. 11 is a bottom view of a personal mobility device according to the novel design in a closed/collapsed configuration; and,

FIG. 12 is a perspective view of a personal mobility device according to the novel design in a closed/collapsed configuration.
